UNITED STATES PATENT OFFICE

FRANK O. BERGSTRAND, OF WORCESTER, MASSACHUSETTS

COASTING ATTACHMENT FOR SHOES

Application filed December 21, 1931. Serial No. 582,217.

This invention relates to an attachment to be made of comparatively thin and light metal like galvanized iron or the like, apply to a shoe for use principally in coasting, although capable also of other uses.

The principal objects of the invention are 5 to provide a detachable toe cap, preferably of metal, with means on the side for use in steering and with a member on the front or end of the toe for use particularly in starting the sled with the foot; to provide a simple 10 and convenient construction which can be sold at a low price and to provide, in association with the part used in starting the sled, a spur for assistance in walking on the ice.

Other objects and advantages of the invention will appear hereinafter.

Reference is to be had to the accompanying drawing, in which

Fig. 1 is a plan of a toe guard constructed in accordance with this invention;

20 Fig. 2 is a side view showing it as applied to a shoe, and

Fig. 3 is a plan of the blank of sheet metal used in making the device.

As stated, this invention relates to a so-called toe guard for use with shoes, which is particularly adapted for use in coasting on snow or ice. It is made from a blank 10 of sheet metal having two side flanges 11, each one provided with a slot 12, which slots are 25 in alignment in the blank and are adapted to overlap when these two flanges are brought together. The blank also has a central forwardly projecting projection 13 also having a longitudinal slot 14. There are perforations 30 15 and 16, preferably, although these perforations are not essential. The three slots 12 and 14 are brought together by bending the sides upwardly around the top and the front projection 13 up and backwardly 35 to cover them. A bolt 17 is inserted through the three slots.

The reason for having the slots 12 is to provide for using the same blank to make different sizes of toe protectors. These slots can 40 overlap as much as desired in order to get the right size and then the bolt can be introduced and the nut screwed up to hold it. The length also can be adjusted in the same way on account of the slot 14. This constitutes 45 the supporting part of the structure and can

50 On the toe of the structure just described is riveted a separate piece of stronger iron or preferably sheet steel 20. This is provided with two spurs 21 bent downwardly on the bottom of the article to serve the usual purpose of such spurs, namely, to prevent slipping when walking on the ice or snow. Two slots are cut into this member 20, on the 55 front end, in a vertical direction and the metal cut from them is bent out to form two spurs 22, which are used in pushing the sled, the foot being wrong side up at that time with the toe extending downwardly and back- 60 wardly.

At the end is a flange 23 which also serves a similar purpose. When the foot is extended over fully in inverted position, this flange can be used to dig into the snow or 65 ice for the purpose of starting the sled and giving it some speed.

On the side of the member 10 is riveted a horizontal outwardly projecting flange 24 to be used in steering and also to bring the 70 sled to a sudden stop or slow it down.

This constitutes a simple and inexpensive device and provides means whereby a sled can be steered in all ways that may be necessary, not only without any contact of the 75 shoe with snow or ice, but special provisions are provided by which this steering is more effective.

Although I have illustrated and described only one form of the invention I am aware 80 of the fact that modifications can be made therein by any person skilled in the art without departing from the scope of the invention as expressed in the claims. Therefore, I do not wish to be limited in this respect, 85 otherwise than as set forth in the claims, but what I claim is:—

1. As an article of manufacture, a sheet metal blank for a toe guard having a central portion adapted to constitute the sole of the 90 device and two side flanges having transverse slots in alignment with each other adapted to be bent over into contact to receive a bolt through the slots to secure the side projections in adjusted position, and a front pro- 95

jection having a longitudinal slot in the end adapted to be bent up into contact with the sides with the slot in registration with the first named slots to receive the same bolt.

- 5 2. As an article of manufacture, a toe guard comprising a piece of sheet metal having a central part adapted to cover the bottom of the shoe at the toe and two side projections adapted to be bent up around the
10 sides of the shoe and having transverse slots through which a bolt can be passed to secure them together in adjustment.
3. As an article of manufacture, a toe guard having a bottom and integral sides extending up over the top and adjustably secured together and a front projection extending upwardly around the toe portion and then backwardly and a bolt adjustably securing the toe portion to the two sides.
- 20 4. As an article of manufacture, a toe guard adapted to receive the toe of a shoe therein and having secured to the front portion thereof a convex piece of sheet metal having a downwardly and forwardly extending projection at a distance above the sole of the shoe and a rounded central end above said projection extending upwardly on the shoe, for the purpose described.

30 In testimony whereof I have hereunto affixed my signature.

FRANK O. BERGSTRAND.
